UNITED STATES PATENT OFFICE.

ARTHUR E. ENGLAND, OF ROCKAWAY BEACH, NEW YORK.

ANTISEPTIC TOOTHBRUSH HOLDER.

Application filed December 3, 1924. Serial No. 753,566.

To all whom it may concern:

Be it known that I, ARTHUR E. ENGLAND, a citizen of the United States, residing at Rockaway Beach, county of Queens, State of New York, have invented a certain new and useful Improvement in Antiseptic Toothbrush Holders, and declare the following to be a full, clear, and exact description of the same, such as will enable others skilled in the art to which it pertains to make and use the same, reference being had to the accompanying drawings, which form a part of this specification.

My invention relates to an antiseptic container for a tooth brush or other similar article. This container is adapted to receive and support a tooth brush and preserve the same in a sanitary condition during such time as the brush is not in use. It is a simple, inexpensive article, capable of being easily disassembled for cleaning and provided with a receptacle for containing a suitable antiseptic fluid, and the invention resides in the construction hereinafter more particularly described in the specification, appended claims and accompanying drawing, in which:

Figure 1 is an elevation of my container carrying a tooth brush.

Figure 2 is a longitudinal sectional view taken on the line 2—2 of Fig. 1.

Fig. 3 is a horizontal sectional view taken on the line 3—3 of Fig. 1.

Fig. 4 is an elevation of the tubular glass container removed from its support.

My complete receptacle comprises a tubular glass container 5 open at one end to receive a tooth brush. This container is supported by a bracket 6 which is adapted to be secured to the wall. This bracket has a shelf portion 7 which is depressed as at 8 to receive one end of the tubular container. The bottom of the depressed portion is cut away to register with the open end of the container, leaving a marginal flange 9 which engages underneath the wall portion of the container to support the same. The tubular container is detachably carried within the depression by means of a pair of opposed lugs 10 each projecting interiorly the

side wall of the depressed portion of the bracket shelf. These lugs engage in slots 11 formed in the exterior surface of the container and extending upwardly from the open end thereof. These slots are so formed that the container may be inserted in the depression, the lugs being received in the said slots, and when the container is rotated the lugs are so engaged in the slots as to releasably lock the container in place.

I provide an annular member 12, which I choose to form of celluloid or other non-rusting material, receivable within the depression in the bracket shelf underneath the end of the container. This annular member is turned upwardly interiorly the container forming an upright annular flange 13 providing an opening through which the brush end of a tooth brush may be inserted against the resistance of the bristles thereof so that the tooth brush when completely inserted will be supported as shown in the drawing.

As an antiseptic carrier I provide an absorbent ring 14 receivable over the upright flange 13 within the container. This ring may be impregnated with a few drops of a suitable antiseptic fluid at such times as may be necessary. It will be seen that the receptacle comprises merely four separate parts, to-wit, the shelf, container, the absorbent ring and the annular member which carries the absorbent ring, and that it could easily be disassembled for purposes of cleaning.

What I claim is:

In a receptacle for a tooth brush, a tubular container open at one end and closed at the other, a bracket having a shelf provided with an annular stepped flange adapted to grip about the container at the open end and having a ledge to engage underneath the wall thereof to support the container, the wall of said container provided with slots and the flange provided with lugs engaged therein to lock the container in place, an independent annular carrier for an antiseptic ring removably supported within said stepped flange having a portion received underneath the end of the container to be held in place thereby and extending in-

wardly from the wall of the container and provided with an upright axial annular ledge for the insertion of a tooth brush, and an absorbent antiseptic ring removably disposed between said ledge and the wall of the container, said ledge adapted to support a tooth brush inserted within the container

whereby the brush bristles will extend over and be supported above the absorbent ring about the ledge. ¹⁰

In testimony whereof, I sign this specification.

ARTHUR E. ENGLAND.
